UNITED STATES PATENT OFFICE.

ALPHEUS FRENCH WARREN, OF BUTLER, OHIO, ASSIGNOR OF ONE-HALF
TO ELROY E. CASSEL, OF SAME PLACE.

ROLLER-BEARING.

SPECIFICATION forming part of Letters Patent No. 627,029, dated June 13, 1899.

Application filed February 15, 1899. Serial No. 705,580. (No model.)

To all whom it may concern:

Be it known that I, ALPHEUS FRENCH WARREN, a citizen of the United States, residing at Butler, in the county of Richland and State of Ohio, have invented new and useful Improvements in Roller-Bearings, of which the following is a specification.

My invention relates to the roller-bearings for the axles of car-wheels and shafts generally; and its object is to provide an improved construction of the same which shall possess superior advantages with respect to efficiency in use.

The invention consists in the novel construction and combination of parts herein-after fully described and claimed.

In the accompanying drawings, Figure 1 is a longitudinal section of a car-axle box provided with my improvements. Fig. 2 is a vertical section on the line $\alpha\alpha$, Fig. 1.

In the said drawings the reference numeral 1 designates the main box, having a cylindrical bore in which fits a cylindrical supplemental box 2, provided at the outer end 25 with a peripheral flange 3, which is secured to the main box by bolts 4. Secured to the said supplemental box by countersunk screws 5 are wear-plates 6. Located in said supplemental box is a series of loose rollers 7, which 30 surround and bear against the journal 8 of a car-axle 9. This journal passes through openings in one end of the main box and the wear-plate secured thereto. At the front side the supplemental box and its wear-plate are 35 formed with openings 11, which communicate with an oil-feed reservoir 10, bolted to said supplemental box by bolts 12 and which

is designed to contain a suitable lubricating material. Passing through the outer side of said oil-reservoir are set-screws 13, the inner ends of which are formed with conical points adapted to engage with openings leading to the interior of the supplemental box.

In use the journal will rotate in contact with the rollers, which latter will revolve in the supplemental box, by which means the friction is reduced to a minimum. The supply of oil or lubricating material is regulated by the screw 13, by turning which the feed is increased or diminished, as the case may be. 50

Having thus fully described my invention, what I claim is—

In a journal-bearing, the combination with the main box having a cylindrical bore and the journal, of the supplemental box fitting in said main box closed at the outer end and provided with oil-openings in said closed end, the flange, the bolts securing it to the main box, the oil-reservoir secured to said supplemental box, the set-screws passing through openings in the end of said supplemental box, and having their inner ends reduced forming valves engaging with said oil-openings, the wear-plates secured to said supplemental box and the loose rollers interposed between said journal and said supplemental box, substantially as described.

In testimony whereof I have hereunto set my hand in presence of two subscribing witnesses.

ALPHEUS FRENCH WARREN.
